C. A. HUSE & J. G. DOUTY.
ELECTRIC RAILWAY SYSTEM.
APPLICATION FILED SEPT. 17, 1907.

920,339.

Patented May 4, 1909.

UNITED STATES PATENT OFFICE.

CHARLES A. HUSE AND JOHN G. DOUTY, OF WILLIAMSPORT, PENNSYLVANIA, ASSIGNORS
TO SIMPLEX SURFACE CONTACT COMPANY.

ELECTRIC-RAILWAY SYSTEM.

No. 920,339.

Specification of Letters Patent.

Patented May 4, 1909.

Application filed September 17, 1907. Serial No. 393,299.

To all whom it may concern:

Be it known that we, CHARLES A. HUSE and JOHN G. DOUTY, citizens of the United States, residing at Williamsport, in the 5 county of Lycoming and State of Pennsylvania, have invented new and useful Improvements in Electric-Railway Systems, of which the following is a specification.

This invention relates to electric railway systems of that general class in which spaced contact switch-boxes are arranged at intervals along the road and are successively connected to a feed wire or main conductor by the movement of the switches 10 from the attractive influence of magnets suspended from the car, these switch-boxes delivering their current in successive order to a collecting shoe carried by the car.

One of the objects of the invention is the 20 provision of a system of the character referred to in which only one set of electro-magnet windings are employed to operate the contact switches and these magnets are adapted to be connected in a battery circuit for initially starting the car and to be connected at other times with the supply 25 mains of the system irrespective of whether the controller of the car is in either "on" or "off" position.

30 A further object is the employment of electro-magnets, the windings of which are of comparatively large gage wire and are of great mechanical strength and durability so that breakage and burning out is minimized. In this respect, the present invention overcomes the disadvantages of such systems heretofore proposed in which shunt windings are employed in connection with the series windings for the purpose of maintaining the electro-magnets energized while the controller of the car is open, the shunt winding being found objectionable owing to the comparatively great expense and difficulty in manufacturing and maintenance.

45 Another object is to provide a permanently closed resistance containing shunt between the electro-magnets which are arranged in series parallel relation, and the return conductor of the system so that a 50 path is provided for the current through the electro-magnets when the controller is open, the resistance being of such a value

as to effectually cut off the flow therethrough when the motor containing circuit of the system is closed through the controller.

The invention has as a further object the employment of an automatic means in combination with the arrangement above set forth whereby the battery circuit will be automatically opened as soon as the energized electro-magnets cause the shoe of the car to be electrically connected with the supply conductor of the system through the contact switches, thus rendering it unnecessary for the motorman to manually cut the 60 battery circuit out of service.

With these objects in view and others as will appear as the description proceeds, the invention comprises the various novel features of construction and arrangement of 70 parts which will be more fully described hereinafter and set forth with particularity in the claims appended hereto.

In the accompanying drawing which illustrates one of the embodiments of the invention, Figure 1 is a diagram of that portion of the system comprising the apparatus and wiring of a car and a section of a track, together with some of the contact switches. Fig. 2 is a transverse section of the collecting shoe and electro-magnet pole strips associated therewith.

Similar reference characters are employed to designate corresponding parts in the views of the drawing.

Referring to the drawing, 10 designates one of the rails on which the cars travel and which serves as the return conductor of the system, and suitably arranged with respect to the track rails are contact switch boxes 90 designated generally by 11 which are successively operated by the electro-magnets on a car as it approaches so as to connect the electric equipment of a car with a feed conductor. Each contact switch comprises a 95 pair of oppositely disposed unwound pole pieces 12 and 13 between which is mounted an oscillating armature 11^a that carries a contact 11^b that is adapted to be brought into engagement with a stationary contact 100 or conductor 14 when a magnetic flux is produced through the pole pieces by the approach of the energized electro-magnets on a car, the armature being normally biased in

such a manner as to open the switch when the flux through the pole pieces is *nil*. For a better understanding of the construction and operation of the contact switches, reference is to be had to our pending application Serial No. 393,298, filed concurrently herewith. The stationary contacts or conductors of the switches are connected with the supply main or feeder 15 and when any switch is closed, current passes from the conductor 15, through the conductor 14, contact 11^b, armature 11^a and metallic box or casing of the switch to the collecting shoe of the car which runs in contact with the portion 16 on the casings of the switches 11. The switch boxes are spaced apart along the track a suitable distance from each other and the shoe 20 suspended on the car is of such a length as to bear at least on one switch so that current can be supplied continuously to the propelling motor or motors. Extending longitudinally of the car and preferably, although not necessarily at opposite sides of the shoe 20, as shown in Fig. 2, are two pole strips 21 and 22, which, together with the shoe are mounted on hangers 19 for suspending the parts from the bottom of the car. On each pole strip are mounted electro-magnets 23 and those of each strip are connected in series relation, while both groups are connected in multiple in the various circuits of the system. On the car is installed a battery 25 of the secondary or accumulator type and this battery is connected by a wire 26 with the electro-magnets 23 and a current passing through the electro-magnets returns to the battery through a conductor 27 in which is included a manually operated cut-out switch 28. The controller 30 is connected with the conductor 27 by a wire 29 and leading from the controller is a conductor 31 that connects with the propelling motor 32 and this motor is connected with the return side of the system by a conductor 33. The shoe 20 is connected with a wire 35 which includes a circuit breaker 34 and the wire 35 is connected with a series solenoid 36 which is adapted to control the battery circuit and from the solenoid is a wire 37 that connects with the electro-magnets 23. The solenoid is provided with a core 38 and has a bridging contact 39 adapted to engage the contact points 40 included in the conductor 27. Between the electro-magnets 23 and return conductor 10 is a resistance winding containing shunt 43, the resistance coil being designated by 44.

In practice, the system is brought into operation by the motorman first closing the cut-off switch 28 so as to complete the battery circuit, it being understood that when no current is flowing in the solenoid 36 the bridging contact 39 by its weight combined with that of the core 38 will engage with the

contact points 40, so that current will flow 65 as soon as the switch 28 is closed. The circuit for the battery current includes the conductor 26, solenoid 36, conductor 27, switch 28, contact piece 39 and thence to the battery 25. The magnets being thus energized 70 will establish a magnetic flux through the pole pieces 12 and 13 of the approximate contact switch box so that the collecting shoe 20 will be connected with the feeder 15. The circuit is then completed through the 75 contact box 11, shoe 20, conductor 35, circuit closer 34, winding of the solenoid 36, conductor 37, electro-magnets 23, shunt 43, resistance 44 and return conductor 10. The passage of the current through the solenoid 80 will cause the latter to automatically cut the battery circuit out of service and sufficient current passes through the grid resistance 44 to maintain the electro-magnets in operative condition. To start the car it is 85 then merely necessary for the motorman to throw on the controller in the usual manner thereby closing the path from the electro-magnets through the controller, conductor 31, motor 32, conductor 33 and thence to the 90 return conductor 10, there being practically little or no current passing through the resistance 44 by reason of the making of this new relatively low resistance path through 95 the motor. It will be noted that the resistance containing conductor 43 is permanently connected in circuit so that as soon as the controller is thrown to off position, as in making a stop or coasting, the current from the electro-magnets will pass to the return conductor through the resistance 44. When the car is taken out of service for the night, it is merely necessary for the motorman to open the switch 28 so as to reserve the strength of the battery 25 and when the current is cut off at the power-station, the solenoid 36 becomes deenergized and thus permits the bridging contact 39 to drop to normal position so that the battery circuit can be again cut in by the closing of the switch 28, 110 when required.

From the foregoing description taken in connection with the accompanying drawing, the advantages of construction and of the method of operation will be readily apparent to those skilled in the art to which the invention appertains, and while we have described the principles of operation of the invention, together with the apparatus which we now consider to be the best embodiment thereof, we desire to have it understood that the apparatus shown is merely illustrative and such changes may be made when desired as are within the scope of the claims.

Having thus fully described the invention, what is claimed as new is:—

1. In a system of the class described, a main feed wire, spaced switch-boxes and

electro-magnetically actuated switches therein, car carried electro-magnets controlling said switches and having only single windings of low resistance, a motor circuit in which 5 said electro-magnets are connected, a motor controller, and an auxiliary return circuit independent of the circuit connections through the controller and including a resistance for preserving the continuity of the 10 circuit of the electro-magnets when the controller is open.

2. In a system of the class described, a main conductor, a plurality of spaced switch boxes, electro-magnetically actuated switches 15 therein, car-carried electro-magnets controlling said switches, a motor, a motor circuit in which the electro-magnets are connected in series parallel, and an auxiliary return connection in series with the electro 20 magnets to form a constantly closed by-pass for current and including a resistance higher than that of the motor circuit and arranged to connect the electro-magnet circuit to the return side of the system when 25 the motor circuit is open.

3. In an electric railway system, the combination of contact switch boxes, a main supply circuit, switches adapted to be connected with the circuit, single coil electro-magnets 30 controlling the switches, a local circuit connected with the electro-magnets and containing a source of electromotive force, a resistance containing shunt between the electro-magnets and the return side of the 35 supply circuit, a motor containing circuit connected with the electro-magnets and return side of the supply circuit and a controller included in the motor containing circuit, said shunt being connected between 40 the controller and all the electro-magnets for permitting current to flow at all times through the latter.

4. In an electric railway system, the combination of electro-magnetically actuated 45 contact switch boxes, and a supply circuit, with a plurality of car carried electro-magnets having single windings, a motor circuit, a controller in the circuit supplying the motor through the electro-magnets, and a 50 permanently closed resistance containing path between the electro-magnets and return side of the said supply circuit for permitting current to flow through the windings of the electro-magnets when the motor 55 controller is open; said path and motor circuit being arranged in parallel relation between the two sides of the supply circuit.

5. In an electric railway system, the combination of a main supply circuit, and contact devices adapted to be automatically connected in and disconnected from said circuit, with a plurality of car carried electro-magnets having single windings, a local supply circuit connected with the electro-

magnets, means for connecting the electro-magnets, with the main supply circuit, an automatic device for opening the local circuit when the electro-magnets are supplied from the main circuit, and a resistance containing conductor permanently connected in 70 series between the electro-magnets and the return side of the main supply circuit.

6. In an electric railway system, the combination of a main supply circuit, and contact devices adapted to be connected with the 75 circuit, with car carried electro-magnets for connecting the contact devices with the supply circuit, a car carried collector adapted to engage the devices, a conductor connecting the collecting device with the electro-magnets, a motor containing conductor between the electro-magnets and return side of the main supply circuit, a local supply circuit connected with the electro-magnets, a controller for the motor, automatic means for opening the local supply circuit when the electro-magnets are connected with the main supply circuit, a manually-operated switch in circuit with the said 80 means, and a permanently closed resistance 90 containing conductor between the electro-magnets and return side of the main supply circuit.

7. In an electric railway system, the combination of a main supply circuit, and contact devices adapted to be connected with the circuit, with a plurality of car-carried electro-magnets, a local circuit in which the electro-magnets are connected in series relation, a current collector co-operating with the contact devices and connected with the electro-magnets, a motor containing conductor between the electro-magnets and return side of the main supply circuit, a controller in the conductor, a conductor arranged in shunt 100 relation with the motor containing conductor and including a resistance of such value as to permit sufficient current to flow to energize the electro-magnets when the circuit is opened through the motor-containing conductor, and means dependent upon a supply of current from the main circuit to the electro-magnets for automatically opening 105 the local supply circuit.

8. In an electric railway system, the combination of a main supply system, and contact devices adapted to be connected therewith, a plurality of electro-magnets having single windings of comparatively low resistance for rendering the contact devices operative, a local supply circuit connected with the said windings for energizing the same, a circuit connecting the contact devices with the electro-magnets, a series solenoid in the circuit, means controlled by the solenoid for opening the local circuit, a motor circuit between the main supply circuit and electro-magnets for receiving currents through the 115 120 125

windings of the latter, a controller, and a resistance containing conductor between the main circuit and electro-magnets for maintaining a flow of current through the windings of the latter when the motor controller is opened and when the solenoid-controlled means closes the local circuit.

In testimony whereof we affix our signatures in presence of two witnesses.
